Primary Examiner — Katherine Glennon(74) *Attorney, Agent, or Firm* — Paratus Law Group, PLLC(57) **CLAIM**

The ornamental design for a protective smart watch cover, as shown and described.

DESCRIPTION

FIG. 1 is a front, top, and right-side perspective view of a protective smart watch cover, showing my new design; FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front, bottom, and left-side perspective view thereof; and,

FIG. 9 is a front, top, and right-side perspective view thereof, showing the protective smart watch cover in a configuration of use.

The broken lines shown in FIG. 9 depict environmental subject matter only and form no part of the claimed design.

1 Claim, 7 Drawing Sheets(56)
